TOBACCO PIPE CLEANING DEVICE

John W. Bentley, Chicago, Ill.

Application July 27, 1946, Serial No. 686,792

12 Claims. (Cl. 285—2)

1

My invention relates to tobacco pipe cleaning devices, and consists of a simple instrumentality made of resilient material, such as rubber, or cork, and which is used in connection with water, or air pressure means, causing the fluids to course through a smoker's pipe to effectuate the cleaning operation.

An important object of my invention is to provide a device of the aforementioned character, which consists of a plug element made of resilient material, and having therein means for connection to the outlet of water pressure, or air pressure means, and means for receiving the pipe stem of a tobacco pipe.

Another object of my invention is to provide a device of the aforementioned character which is adapted to establish a leak-proof or sealed communication when intermediately positioned between air, or water, pressure means, and pipe stem means.

A further object of my invention is to provide a device of the aforementioned character made of resilient material which is adapted to establish communication between water pressure means or air pressure means, and the cavity in the pipe bowl.

A further object of my invention is to provide a plug-type of intermediate seal connection, which consists of a substantially small peripherally cylindrical portion having a frusto-conical portion on one side of the said peripheral portion, and a frusto-conical portion on the opposite side of the said peripheral portion.

A further object of my invention is to provide a slightly modified form of seal plug means of the aforementioned character, which is provided with a peripherally cylindrical portion, a frusto-conical portion on one side of the said peripherally cylindrical portion, and a spherical portion on the opposite side of the said frusto-conical portion.

A further object of my invention is to provide a device of the aforementioned character which consists of a peripherally cylindrical portion, and two spherical portions contiguous to each side of the said peripherally cylindrical portion.

A further object of my invention is to provide a pipe cleaning seal plug of the aforementioned character, which is simple in construction, practical and efficient in its operation, effectively cleaning a smoker's pipe rather expediently, and an article which is of such simple elemental construction as to warrant manu-

2

facture thereof economically in quantity production.

Other features, objects, and ancillary advantages inherent in my invention will become apparent from an examination of the accompanying drawings, having further reference thereto in the ensuing description, wherein like symbols are used to designate like parts, and in which:

Fig. 1 is a front view with certain portions indicated in cross-section, clearly elucidating the structure and application of one form of my invention.

Fig. 2 is an end view of Fig. 1, with certain portions broken away and shown in section to more clearly depict the structural relationship of the parts.

Fig. 3 is a plan view of one form of my invention.

Fig. 4 is a front view of Fig. 3.

Fig. 5 is a bottom view of Fig. 4.

Fig. 6 is a cross-sectional view taken, substantially, on the line 6—6 of Fig. 5.

Fig. 7 is a transverse cross-sectional view, taken substantially, on the line 7—7 of Fig. 5.

Fig. 8 is a plan view of a slightly modified form of my invention.

Fig. 9 is a cross-sectional view of Fig. 8.

Fig. 10 is a sectional view indicating another method of using the various forms of my invention.

Fig. 11 is a view similar to Fig. 10 showing the form of my invention used in Fig. 10, it being used in inverted position to effectuate the same results.

Fig. 12 is a cross-sectional view similar to Fig. 10 showing air pressure means being used, as distinguished from the water pressure means used in Figs. 10 and 11.

Referring now to the various views, 13 illustrates the nozzle of a water tap or other means of liquid pressure, having an outlet bore 14 therein, and showing one form of my invention generally designated 15, assembled in connection with a tobacco pipe generally designated 21, the view depicting the process of actually cleaning the pipe by means of ingress of the water pressure through the stem conduit, and egress of the liquid and the material being cleaned from the pipe from the cavity 24 in the bowl 23 of the pipe 21.

My invention, generally designated 15, in this particular instance, consists of a peripherally cylindrical portion 18, of shallow dimension, having contiguous to the top thereof, a frusto-conical section 16, and contiguous to the bottom 55 thereof another frusto-conical section 17. The

bottom portion is provided with an elongated slot 20 to fit snugly over a pipe stem 22, which permits the liquid from the tap 13 to flow therethrough, as well as through the conduit 33, or the passage 33, in the pipe stem 22.

Figs. 3, 4 and 5 show the detail structure of one form of my invention, namely, the particular form containing the oppositely disposed frusto-conical section.

Figs. 6 and 7 show another form of my invention, wherein the same is generally designated 25, and differs from the form illustrated in Figs. 3, 4 and 6 only in the structure of the portion contiguous to the bottom of the peripherally cylindrical portion 18, which instead of being a frusto-conical portion, in this particular instance is a spherical portion designated 27, the top portion thereof being frusto-conical, and designated 26 being similar to the frusto-conical section 16 of the form illustrated in Figs. 3, 4 and 5.

In Fig. 9, I show a slightly modified form of my invention, which is made up to have contiguous to the peripherally cylindrical portion 18 two spherical sections, one at the top designated 29, and one at the bottom designated 30, this form of my invention being generally designated 28. All forms are provided with the stem receiving opening 20, and the passage-way or conical bore 19 for establishing communication between the source of pressure and the tobacco pipe to be cleaned.

In Figs. 10 and 11, I show that form of my invention, generally designated 25 being used in connection with liquid pressure means from the tap, and the difference between Figs. 10 and 11 is, primarily, in the showing of the universal method or manner in which all the forms of my invention 25, 28 and 15 may be used, i. e., either in upright, or inverted positions as indicated by Figs. 10 and 11.

Fig. 12 shows the use of my device in connection with cleaning a smoker's pipe, when the pressure is supplied by an air hose 31, having a valve head 32, which will seal about the opening of the bore 19, and thus cause the air pressure to flow through the pipe.

In cleaning the pipe, as illustrated in Figs. 1 and 2, the contaminated liquid is caused to flow from the stem, through the pipe, and exit through the bowl cavity 24.

In Figs. 10, 11 and 12, the reverse procedure is indicated, in that either the fluid or the liquid pressure is utilized between the pipe in the reverse operation, that is, namely, by causing either the air pressure, or the liquid pressure to flow from the bowl cavity 24 through the pipe, and exit at the forward portion of the pipe stem passing through the passage or conduit 33.

All of the forms of my invention may be made of rubber, or similar resilient material, either of natural or synthetic type, or cork, or similar material; however, I have found that a resilient, or rubber-like material is the most ideal, especially in view of the fact that the cavity, or slotted portion 20, of necessity, must be receptive to different widths of pipe tips.

I believe, I have herein disclosed, and described, rather succinctly, the structure, the application, and use of various slightly modified forms of my invention, and inasmuch as the same are susceptible of modifications, improvements, and alterations, I hereby reserve the right to all such modifications, alterations, and improvements coming within the scope and spirit of my invention, as

well as any of those that are impliably suggested or embraced in the accompanying drawings, and also all those that fall within the purview of the foregoing description; my invention to be limited only by the subjoined claims.

Having thus described and revealed my invention, what I claim as novel, and desire to secure by Letters Patent, is:

1. A pipe cleaning device comprising, a plug made of resilient material and provided with a peripherally cylindrical central portion having reduced upper and lower portions contiguous to opposed surfaces of the said cylindrical central portion, and an axial bore therethrough terminating in an elongated recess adapted to receive and to retain frictionally removably and interchangeably the tips of pipe mouth-pieces.

2. A pipe cleaning device comprising, a plug made of resilient material and provided with a peripherally cylindrical central portion having frusto-conical upper and lower portions contiguous to opposed surfaces of the said cylindrical central portion, and an axial bore therethrough terminating in an elongated recess adapted to receive and to retain frictionally removably and interchangeably the tips of pipe mouth-pieces.

3. A pipe cleaning device comprising, a plug made of resilient material and provided with a peripherally cylindrical central portion having an upper frusto-conical portion and a lower partially spherical portion each contiguous to opposed surfaces of the said cylindrical central portion, and an axial bore therethrough terminating in an elongated recess adapted to receive and to retain frictionally removably and interchangeably the tips of pipe mouth-pieces.

4. A pipe cleaning device comprising, a plug made of resilient material and provided with a peripherally cylindrical central portion having partially spherical upper and lower portions contiguous to opposed surfaces of the said cylindrical central portion forming a spheroid, and an axial bore therethrough terminating in an elongated recess adapted to receive and to retain frictionally removably and interchangeably the tips of pipe mouth-pieces.

5. A pipe cleaning device comprising, a plug made of resilient material and provided with a peripherally cylindrical central portion having reduced upper and lower portions contiguous to opposed surfaces of the said cylindrical central portion, and an axial bore therethrough terminating in an elongated recess adapted to receive and to retain frictionally removably and interchangeably the tips of pipe mouth-pieces, the said cleaning device adapted to form a pressure communication seal when interposed between pressure means and when secured to a pipe stem.

6. A pipe cleaning device comprising, a plug made of resilient material and provided with a peripherally cylindrical central portion having frusto-conical upper and lower portions contiguous to opposed surfaces of the said cylindrical central portion, and an axial bore therethrough terminating in an elongated recess adapted to receive and to retain frictionally removably and interchangeably the tips of pipe mouth-pieces, the said cleaning device adapted to form a pressure communication seal when interposed between pressure means and when secured to a pipe stem.

7. A pipe cleaning device comprising, a plug made of resilient material and provided with a peripherally cylindrical central portion having an upper frusto-conical portion and a lower par-

5 partially spherical portion each contiguous to opposed surfaces of the said cylindrical central portion, and an axial bore therethrough terminating in an elongated recess adapted to receive and to retain frictionally removably and interchangeably the tips of pipe mouth-pieces, the said cleaning device adapted to form a pressure communication seal when interposed between pressure means and when secured to a pipe stem.

8. A pipe cleaning device comprising, a plug made of resilient material and provided with a peripherally cylindrical central portion having partially spherical upper and lower portions contiguous to opposed surfaces of the said cylindrical central portion forming a spheroid, and an axial bore therethrough terminating in an elongated recess adapted to receive and to retain frictionally removably and interchangeably the tips of pipe mouth-pieces, the said cleaning device adapted to form a pressure communication seal when interposed between pressure means and when secured to a pipe stem.

9. A pipe cleaning device comprising, a plug made of resilient material and provided with a peripherally cylindrical central portion having reduced upper and lower portions contiguous to opposed surfaces of the said cylindrical central portion, and an axial bore therethrough terminating in an elongated recess adapted to receive and to retain frictionally removably and interchangeably the tips of pipe mouth-pieces, the said cleaning device adapted to form a pressure communication seal when interposed between pressure means and the bowl cavity of a pipe.

10. A pipe cleaning device comprising, a plug made of resilient material and provided with a peripherally cylindrical central portion having frusto-conical upper and lower portions contiguous to opposed surfaces of the said cylindrical central portion, and an axial bore therethrough

terminating in an elongated recess adapted to receive and to retain frictionally removably and interchangeably the tips of pipe mouth-pieces, the said cleaning device adapted to form a pressure communication seal when interposed between pressure means and the bowl cavity of a pipe.

11. A pipe cleaning device comprising, a plug made of resilient material and provided with a peripherally cylindrical central portion having an upper frusto-conical portion and a lower partially spherical portion each contiguous to opposed surfaces of the said cylindrical central portion, and an axial bore therethrough terminating in an elongated recess adapted to receive removably and interchangeably the tips of pipe mouth-pieces, the said cleaning device adapted to form a pressure communication seal when interposed between pressure means and the bowl cavity of a pipe.

12. A pipe cleaning device comprising, a plug made of resilient material and provided with a peripherally cylindrical central portion having partially spherical upper and lower portions contiguous to opposed surfaces of the said cylindrical central portion forming a spheroid, and an axial bore therethrough terminating in an elongated recess adapted to receive removably and interchangeably the tips of pipe mouth-pieces, the said cleaning device adapted to form a pressure communication seal when interposed between pressure means and the bowl cavity of a pipe.
